UNITED STATES PATENT OFFICE.

ALBERT COWELL, OF KIDDERMINSTER, ENGLAND.

DESIGN FOR CARPET.

Specification forming part of Design No. 6,512, dated March 25, 1873.

To all whom it may concern:

Be it known that I, ALBERT COWELL, of Kidderminster, Worcestershire, in England, have invented a new and original Design for Carpets; and I do hereby declare that the following is a full, clear, and exact description thereof, which will enable others skilled in the art to make and use the same, reference being had to the accompanying photographic illustration forming part of the specification.

The nature of my design is fully represented in the accompanying photographic illustration, to which reference is made.

This design consists in a white mottled ground, *a*, on which there is a series of irreg-

ular circular white borders, *b*, inclosing a dark-colored central square figure, *c*. The figures *a* are alternated by smaller figures, *d*, formed of dark lines inclosing a central cross, *e*, and upon either side of the said figures *a* and *b*; and on the said mottled white ground, there are dark squares *f*, each inclosing a light-colored center, *g*. The said figures are placed in rows on the white mottled ground, as set forth.

I claim as my invention—

The design for carpets, as shown.

ALBERT COWELL.
